US00D831610S

(12) **United States Design Patent** (10) **Patent No.:** **US D831,610 S**
(45) **Date of Patent:** **** Oct. 23, 2018**

(54) **HEADPHONES**

- (71) Applicant: **Apple Inc.**, Cupertino, CA (US)
- (72) Inventors: **Shota Aoyagi**, San Francisco, CA (US); **Robert Boyd**, Los Angeles, CA (US); **Robert Brunner**, San Francisco, CA (US); **Monica Fernandez**, Los Angeles, CA (US); **Christopher Kuh**, San Francisco, CA (US); **Christopher J. Stringer**, Woodside, CA (US)
- (73) Assignee: **Apple Inc.**, Cupertino, CA (US)
- (**) Term: **15 Years**
- (21) Appl. No.: **29/622,980**
- (22) Filed: **Oct. 20, 2017**

Related U.S. Application Data

- (63) Continuation of application No. 29/575,696, filed on Aug. 26, 2016, now Pat. No. Des. 817,301.
- (51) **LOC (11) Cl.** **14-01**
- (52) **U.S. Cl.**
USPC **D14/205**

(57) **CLAIM**

The ornamental design for headphones, as shown and described.

DESCRIPTION

FIG. 1 is a front perspective view of headphones showing the claimed design;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a top view thereof;

FIG. 8 is a reference view showing an enlarged portion of FIG. 1;

FIG. 9 is a reference view showing an enlarged portion of FIG. 2;

FIG. 10 is a reference view showing an enlarged portion of FIG. 3;

FIG. 11 is a reference view showing an enlarged portion of FIG. 4; and,

FIG. 12 is a reference view showing an enlarged portion of FIG. 6.

The broken lines in the figures show portions of the headphones that form no part of the claimed design.

1 Claim, 6 Drawing Sheets
